UNITED STATES PATENT OFFICE.

ROBERT A. SCRANTON, OF NEW YORK, N. Y., ASSIGNOR TO HIRAM TYREE, OF NEW YORK, N. Y.

COMBINED SEWING-MACHINE CABINET AND DESK.

1,047,996.

Specification of Letters Patent. Patented Dec. 24, 1912.

Application filed April 11, 1912. Serial No. 890,199.

To all whom it may concern:

Be it known that I, ROBERT A. SCRANTON, a citizen of the United States, residing at New York, in the county of New York and State of New York, have invented certain new and useful Improvements in Combined Sewing-Machine Cabinets and Desks, of which the following is a specification.

The present invention relates to an article of furniture and has particular reference to such a device adapted to serve as a sewing machine cabinet and to be readily converted into a desk to be used as such.

An important object of the invention is to provide a device of the above mentioned character, the parts of which may be easily operated to convert the device from a sewing machine cabinet into a desk, the elements of the sewing machine being concealed when the device is in use as a desk.

A further object of my invention is to provide a combined sewing machine cabinet and desk, which is simple in construction, easy to operate, and cheap to manufacture.

Other objects and advantages of the invention will be apparent during the course of the following description.

In the accompanying drawings forming a part of this specification and in which like numerals are employed to designate like parts throughout the same, Figure 1 is a perspective view of the device as a whole, showing it in use with the sewing machine in its operative position, Fig. 2 is a front elevation of the same, parts being shown in section and parts in elevation, the sewing machine being in its concealed position with the top section closed, Fig. 3 is a transverse vertical sectional view taken on line 3—3 of Fig. 2, Fig. 4 is a side view of the pitman, Fig. 5 is an edge view of the same, Fig. 6 is a detail sectional view taken through a detachable bearing carried by the pitman, and, Fig. 7 is a perspective view of a stationary detachable bearing.

In the drawings wherein for the purpose of illustration, I have shown a preferred embodiment of my invention, the numerals 1 and 2 designate end pedestals or frames, comprising outer and inner legs 3 and 4. Disposed between the outer legs 3 are transverse end pieces or panels 5 and disposed between the inner legs 4 are transverse panels or walls 6. The panels or walls 6 are

much shorter than the end pieces 5, as shown. Disposed between rear legs 3 and 4 are panels or walls 7, as shown. A panel or wall 8 is disposed between the rear inner legs 4 and partially closes one end of the main space 9 which occurs between the end frame or pedestals. A strip 10 connects the upper ends of the forward inner legs 4, as shown. Disposed upon and suitably connected with the upper ends of the pedestals or frames 1 and 2 is an inner top-section 11, to the rear longitudinal edge of which is hinged an outer top-section 12, as shown at 13. When the outer top-section is in its closed position it overlaps and coincides with the inner top-section and when said outer top-section 12 is moved to its open position, as shown in Fig. 1, it is supported by horizontal reciprocating rods 14, which pass through suitable openings formed in the panels or walls 7.

Within the end frame or pedestal 1 are disposed horizontal partitions or shelves 15 and 16, connected by a vertical partition 17, which forms a main storage space 18. Horizontal partitions or shelves 19 are connected with the vertical partition 17, and provide spaces for receiving sliding drawers 20.

The numerals 21 and 22 designate swinging doors which form a false front for the open side of the frame or pedestals 1. The door 21 is preferably hinged at its lower end with the horizontal partition 15, as shown at 24 and the door 22 is preferably hinged at its lower end with the partition 16, as shown at 25. The doors 21 and 22 are provided with knobs 28 or the like.

Disposed within the end pedestal or frame 2 are spaced superposed horizontal partitions or shelves 29, 30 and 31, which are connected with a vertical partition or partitions 32, providing spaces for receiving sliding drawers 33, which are rigidly connected with the inner face of removable heads or doors 34, carrying knobs 35 or the like.

The inner top-section 11 is provided with a preferably rectangular opening 36, within which and adjacent the forward longitudinal wall thereof, is disposed a swinging supporting element or strip 37, which is hinged to the inner top-sections 11, as shown at 38. This holding element or strip 37 cannot swing downwardly below a horizontal position but is free to be elevated or

swung upwardly, as shown in dotted lines in Fig. 3. The supporting element or strip 37 is provided upon its longitudinal edge with a tongue 39, for a purpose to be described.

5 The numeral 40 designates a swinging base of a sewing machine, which is hinged to the inner top section 11, as shown at 41. This base 40 is capable of being swung above the inner top-section 6 so that the supporting element or strip 37 may be swung upwardly out of the path of travel of the base 40 when it is desired to lower the sewing machine to its concealed position. The base 40 is provided upon one longitudinal edge with a tongue 42, for engagement with the tongue 39. Rigidly mounted upon the base 40 is an overhanging bracket-arm 43 of the sewing machine. This sewing machine may be of any well known or preferred type and comprises a grooved wheel 44, engaged by a belt 45.

10 The numeral 46 designates a preferably curved shield, which is pivotally connected with a fixed strip 47, to swing in a vertical plane, by means of hinges 48, equipped with spring means, whereby the shield 46 will automatically move to its elevated position when the sewing machine is raised. The shield 46 is disposed below the inner top-section 11 and forwardly of the sewing machine when the same is in its lowered position, as clearly shown in Fig. 3. Rigidly connected with the horizontal partition 29 of the pedestal or frame 2 by means of bolts 49 or the like are spaced depending preferably substantially U-shaped brackets 50 provided with apertures at their lower ends for rotatably receiving a crank-shaft 51.

15 Rigidly mounted upon this crank-shaft is a large driving wheel 52, provided upon its periphery with the ordinary groove for receiving the belt 45. The partition 30 has an opening 53 formed therethrough for receiving the depending brackets 50 and the wheel 52 and the belt 45 operates through suitable openings formed in the partition 29 and the base 40. The crank-shaft 51 extends outwardly beyond the frame or pedestal 2 and is provided at its free end with a crank-arm 54, rigidly connected therewith, such crank-arm carrying at its free end a pin 55.

20

Disposed between the inner legs 4 are horizontal preferably cylindrical rods 56, which are suitably spaced from the lower ends of the walls or panels 6 for forming openings 57. These horizontal rods may be attached to the legs 4 in any suitable way, but I preferably provide tubular sleeves 58, for receiving the ends of the rods 56. These tubular sleeves carry heads 59, connected with the legs by means of screws or the like. The numeral 60 designates swinging leaves, which are pivotally mounted upon the hori-

zontal rods 56 by hinge leaves 61, as shown. When the leaves 60 are swung to their upper vertical position, they engage the lower ends of the walls 6 and form in effect a continuation of the same. Rigidly mounted upon corresponding faces of the vertically swinging leaves 60 are stationary bearings 62, for removably holding a rock-shaft 63. Each of these stationary bearings (see Fig. 7) is formed of a lower block 64, connected with the leaf 60 by means of screws or bolts. Pivotally connected with the block 64 is an upper block 65, such connection being effected by a hinge 66 attached to the ends of the blocks. The blocks 64 and 65 have an opening 67 formed therethrough for receiving the shaft 63. The upper block 65 is normally held in its closed position by a spring latch 68, which is attached to the block 65, as shown at 69, and carries a tongue 70, which is adapted to engage below the block 64. It is thus seen that by proper manipulation of the latches 68 the blocks 65 may be swung to their open positions and the rock-shaft 63 readily removed from between the sleeves 60. The rock-shaft 60 carries a treadle 71, which is provided at one corner with a pin 72. The treadle 71 is connected with the crank-shaft 51 by a pitman 73, carrying at its opposite ends heads 74. Each of these heads is formed of blocks 75 and 76, pivotally connected at corresponding ends by hinges 77. At each end of the pitman 73 there is formed a reduced screw-threaded portion 78 engaging in a screw-threaded opening formed in the block 75. An opening 79 is formed through each of the heads 74 for rotatably receiving the pins 55 and 72. The block 76 is normally held in its closed position by a spring latch 80, connected therewith by screws 81 and provided near its lower end with a tongue 82, which engage below the block 75. It is thus seen that the blocks 76 may be readily moved to their open positions to permit of the removal of the pitman 73.

25

When the different elements are in their operative positions the operator moves the treadle 71 with the feet in the ordinary way and accordingly drives the sewing machine.

30

When it is desired to use the cabinet as a desk, the base 40 is swung upwardly so that the supporting strip 37 may be swung upwardly to lower the sewing machine and its base 40 to its concealed position. The guard 46 is engaged by the sewing machine and swung downwardly. The supporting strip 37 returns to its normal position when released, subsequently to which the outer top-section 12 is swung to its closed position to overlap the top-section 11. The pitman 73 is disconnected from the crank shaft 51 and the treadle 71 by opening the block 76. The blocks 65 of the stationary bearings 62 are now moved to their open position so that the

treadle and the rock-shaft 63 may be removed from within the opening 9. The pitman 73 and treadle 71 may be advantageously stored within the space 18 of the pedestal or frame 1 and are completely concealed when the door 22 is closed. The leaves 60 are now swung upwardly to assume a vertical position in engagement with the walls 6 of which they now form in effect, 10 a continuation. The wheel 52 being disposed within the frame or pedestal 2, is concealed from view. It is obvious that the drawers 33 may be moved to their open position.

15 It is to be understood that the form of my invention herewith shown and described is to be taken as a preferred example of the same and that certain changes in the shape, size, and arrangement of parts may be resorted to without departing from the spirit of the invention or the scope of the subjoined claims.

Having thus described my invention, I claim:—

25 1. The combination with a cabinet comprising a top and spaced end frames provided upon their inner sides with openings, swinging leaf-closures adapted to be moved upwardly into said openings, bearings 30 mounted upon the faces of the leaf-closures which are disposed innermost with respect to said frames when said leaf-closures are in their elevated positions whereby said bearings are concealed, a treadle provided 35 with supporting means removably mounted within the bearings, a sewing machine mounted upon the cabinet, and driving con-

necting means between the treadle and sewing machine.

2. The combination with a cabinet comprising a top and spaced end frames provided upon their inner sides with openings, a treadle disposed between the end frames and provided with supporting means, and swinging leaf-closures adapted to be moved 45 upwardly into said openings and provided, upon the faces thereof which are disposed innermost with respect to said frames when the leaf-closures are in their elevated positions, with holding means to removably hold 50 said supporting means whereby such holding means will be concealed when said leaf-closures are in their elevated positions.

3. The combination with a cabinet comprising a top and spaced frames, of movable 55 leaves connected with the inner portion of the spaced frames and adapted to be shifted to conceal either of their faces as viewed from the exterior of said spaced frames, a treadle disposed between the spaced frames 60 and provided with supporting means, and bearings removably holding the supporting means and mounted upon corresponding faces of the leaves, whereby such bearings 65 may be concealed as viewed from the exterior of said frames when such leaves are shifted to certain positions.

In testimony whereof I affix my signature in presence of two witnesses.

ROBERT A. SCRANTON.
